DESIGN FOR A READING JACKET

Frances Lardner, Mahwah, N. J., assignor to G. L. Fields, Ltd., New York, N. Y., a corporation of New Jersey

Application September 27, 1941, Serial No. 103,541

Term of patent 7 years

To all whom it may concern:

Be it known that I, Frances Lardner, a citizen of the United States and a resident of Mahwah, in the county of Bergen and State of New Jersey, have invented a new, original, and ornamental Design for a Reading Jacket, of which the following is a specification, reference being had to the accompanying drawing, forming a part thereof.

Fig. 1 is a front view of a reading jacket showing my new design.

Fig. 2 is a rear view of the reading jacket shown in Fig. 1.

I claim:

The ornamental design for a reading jacket, substantially as shown.

FRANCES LARDNER.
